United States Patent Office

Des. 194,107
Patented Nov. 20, 1962

194,107

TELEPHONE OPERATOR'S TURRET

Dietrich J. Klein, 1407 Holly Road, Charlottesville, Va.

Filed Mar. 12, 1962, Ser. No. 69,197

Term of patent 14 years

(Cl. D26—14)

FIGURE 1 is a plan view of the telephone operator's turret according to this invention;

FIGURE 2 is a front elevation of the invention;

FIGURE 3 is an end elevation of the invention, partly in section on the line A—A of FIGURE 1; and

FIGURE 4 is a rear elevation of the invention.

I claim:

The ornamental design for a telephone operator's turret, substantially as shown.
